US00D727892S

(12) **United States Design Patent**
Bowers et al.

(10) **Patent No.:** US D727,892 S
(45) **Date of Patent:** ** Apr. 28, 2015

(54) **NOTEBOOK COMPUTER HOUSING**

(71) Applicant: **Google Inc.**, Mountain View, CA (US)
(72) Inventors: **Andrew Bowers**, San Francisco, CA (US); **Lawrence Lam**, San Jose, CA (US); **Felix Jose Alvarez Rivera**, San Jose, CA (US); **Kenneth Ryan Loo**, San Jose, CA (US); **Ji Lee**, San Francisco, CA (US); **Kevin Tom**, San Francisco, CA (US); **Gad Amit**, San Francisco, CA (US); **Jacqueline Belleau**, San Francisco, CA (US); **Yoshikazu Hoshino**, San Francisco, CA (US); **Amy Han**, Palo Alto, CA (US)

(73) Assignee: **Google Inc.**, Mountain View, CA (US)

(**) Term: **14 Years**

(21) Appl. No.: **29/458,368**

(22) Filed: **Jun. 19, 2013**

Related U.S. Application Data

(62) Division of application No. 29/408,685, filed on Dec. 15, 2011, now Pat. No. Des. 686,613.

(57) **CLAIM**

The ornamental design for a notebook computer housing, as shown and described.

DESCRIPTION

FIG. 1 is a perspective view of a notebook computer housing according to our design;

FIG. 2 is a top view thereof;

FIG. 3 is a bottom view thereof;

FIG. 4 is a front side view thereof;

FIG. 5 is a back side view thereof;

FIG. 6 is a right side view thereof;

FIG. 7 is a left side view thereof;

FIG. 8 is a perspective view of a notebook computer housing according to a second embodiment of our design, of which the bottom and front, back, left, and right side views are similar to FIGS. 1-7;

FIG. 9 is a top view thereof;

FIG. 10 is a perspective view of a notebook computer housing according to a third embodiment of our design, of which the bottom and front, back, left, and right side views are similar to FIGS. 1-7; and,

FIG. 11 is a top view thereof.

Broken lines are environmental only and form no part of the claimed design.

1 Claim, 11 Drawing Sheets
